 Claims priority, application Germany, Aug. 30, 1961,
 B 63,844
 10 Claims. (Cl. 83—130)

The present invention relates to the equipment of the upper turret plate, especially of multiple die punches, with a controlled centre clamp holder and stripper, the design of which is such that this centre clamp holder and stripper may adjust itself to various gauges of sheet metal to be punched.

According to the invention, there is arranged under the turret plate, and preferably under the upper turret plate, a holding and stripping plate, the movement of which precedes that of the punching tool or tools and which holds the material in position until the punching tool has been withdrawn from the workpiece. The movement of the holding and stripping plate may be effected by the same members which also control the movement of the punching tool or tools.

In a preferred embodiment of the invention, there is arranged between the upper turret plate and the holding and stripping plate a compressible body or medium in suitable compression cylinders. Such compressible bodies are, for example, helical springs, plate springs, annular springs or parts made of rubber.

The invention also relates to the various members required either in order to fit a compressible energy accumulator, or necessary in order to correlate the movements of the turret plate and the punching tools on one hand, and the movement of the holding and stripping plate on the other hand.

The invention has the advantage that the holding and stripping member can adapt itself automatically to various thicknesses of the sheet metal to be punched, and that the material is held down already prior to the punching and is held in this position until the tool is withdrawn from the workpiece. Thus all forces are eliminated which affect only the itself and its guides and which thus support or accelerate wear of tools and machine. Furthermore, also the operation is much easier, because the operator need not observe the behaviour of the workpiece as closely as hitherto.

The invention will be further described, by way of example, with reference to the accompanying drawing, showing two embodiments. In the drawing:

FIG. 1 is a cross-section of the turret plate, the resilient member being formed by a spring stack located in the guide column of the upper turret plate.

FIG. 2 is a further embodiment, in which the resilient member is located between the upper turret plate and the holding and stripping plate.

The upper turret plate 1 and the lower turret plate 2 are mounted by means of their spindles 3 and 4 in the machine frame or tool holder 5.

The upper turret plate 1 contains the displaceable die holder 6, connected in the punching position with the ram 7, and moved thereby during the punching in a downward direction; during the upward movement, the die holders 6 and the dies 10' and 10" mounted therein are again withdrawn from the punched workpiece.

The positively controlled holding and stripping plate 8 is mounted by means of its guide column 9 in the spindle 3 of the upper turret plate 1 in a displaceable manner. The movement of the holding and stripping plate 8 whereby the same is placed on to the material to be punched, is advanced relative to the movement of the

2

actual die 10' or 10", mounted in the die holder 6. This holding and stripping plate may be operated, for example, by an eccentric 15 on the driving shaft 25, or a lever linkage coupled with the drive 16 for the ram 7. The stripping plate may also be operated pneumatically or hydraulically.

The holding and stripping force is supplied by an energy accumulator 11, for example, a biased stack of plate springs 11, fitted into the guide column and so dimensioned that it produces the maximum required stripping effort.

The effect of the springs 11 is caused by the fact that they are located between the ram 26 with the head 27 and the guide column, and the ram is located displaceably in the column 9, whilst the ram pin 28 is guided at its lower end in a recess 29.

The parcels of plate springs 11 may also be replaced by other energy storage means, such as helical springs, annular springs, rubber springs, or springs made from rubber-like materials, as well as compressible gases in suitable compression cylinders.

The energy accumulator may also be located at another point of the transmission for operating the holding and stripping plate 8.

25 This holding and stripping plate 8 acts in that way that, when the punching process is initiated, the plate advances in front of the die holder 6 or punch 10' or 10" so that the actual strippers fitted into the holding and stripping plate are placed on the material to be machined. During this movement, the energy accumulator is biased beyond its normal bias. Simultaneously, the die holder 6 with the die 10' or 10" carries out the punching. During the upward movement of the die holder 6 with the die 10' or 10", the strippers remain first on the punched material until the spring stack has been destressed to its normal bias. Since the holding and stripping plate 8, and the strippers 14 rest under spring action on the punched material, the die 10' or 10" may be withdrawn without lifting the workpiece itself.

30 40 Since the holding and stripping plate 8 is not positively connected through the energy accumulator with the actuating mechanism, there are provided, for example, springs 12, for returning the stripper plate 8 to its original position. The spring bolts 13 simultaneously act as guide pins to secure the stripper plate 8 against rotation relative to the upper turret plate 1.

45 FIG. 2 shows another solution, embodying the principle of the invention.

The positively controlled holding and stripping plate 50 8 is also in this case located displaceably by means of its guide column 9 in the spindle 3 of the upper turret plate 1, and also here, the movement whereby the stripper plate 8 is placed on the material to be punched, is advanced relative to the movement of the die 10', 10", mounted in the die holder 6. However, in this embodiment, the holding and stripping plate 8 is moved by means of the sloping plane 21, located on the pull rod 20, for driving the ram through a toggle mechanism, whereby the guide column 9 is lifted and lowered.

55 60 During the downward movement of the ram 7 for the punching process, the holding and stripping plate 8 also moves towards the workpiece and rests thereon before the actual punching starts. Due to the lateral movement of the pull rod 20 in association with the sloping plane 21, the guide column 9 of the holding and stripping plate 8 is released for the downward movement. During the continued downward movement of the ram 7 with the die holder 6 and the die 10' or 10", the actual punching is performed.

65 70 Also here, the holding and stripping force is supplied by energy accumulators, preferably biased plate spring stacks 41, located between the upper turret plate 1 and

the holding and stripping plate 8, the compression of these springs being so dimensioned as to produce the maximum required effort. These plate springs are merely shown diagrammatically.

The stripper plate 8 is secured against twisting relative to the upper turret plate 1 by guide pins 22 which also define the movement of the holding and stripping plate 8 towards the upper turret plate 1.

During the upward movement of the die 10' or 10", the holding and stripping plate 8 with the strippers 14 remains on the material until the die has been withdrawn against the pressure of the energy accumulator 41, and only then is the holding and stripping plate 8 lifted through its guide column 9, by means of the sloping guide plane 21 on the pull rod 20.

The guide plane 21 is so designed and formed that the holding and stripping plate 8 precedes the tool 10' or 10" during the downward movement of the same, and remains on the material during the upward movement of the tool 10' or 10" until the same has been withdrawn from the material.

The action of the holding and stripping plate 8 with fitted strippers 14 according to the invention corresponds to that of a cutting tool with fitted resilient holder and stripper.

The guide plane 21 may cause the vertical movement control of the guide column, for example by means of a roller 32 located at the upper end of the guide column 9 and rolling during the actuation of the pull rod 20 along the guide plane 21.

What I claim is:

1. Rotary punch press including a frame having upper and lower parts, a spindle supported in the upper frame part, an upper revolving turret plate on the spindle, a lower revolving turret plate coaxially journaled in the lower frame part, a plurality of aligned pairs of tools carried by the plates, the plates being rotatable together to bring a desired pair of tools to a working position, a stripper and hold-down plate below the upper turret plate, a guide column supporting the stripper and hold-down plate and axially slidably in the spindle, means for preventing rotation of the stripper and hold-down plate relative to the upper turret plate, drive means for lowering and raising a tool carried by the upper turret plate at the working position, and means for concurrently lowering and raising the stripper and hold-down plate, the downward motion of the latter plate preceding that of the upper turret plate and the upward motion of the said latter plate succeeding that of the upper turret plate.

2. Rotary punch press including a frame having upper and lower parts, a hollow spindle supported in the upper frame part, an upper revolving turret plate on the spindle, a lower revolving turret plate coaxially journaled in the lower frame part, a plurality of aligned pairs of tools carried by the turret plates, the turret plates being rotatable together to bring a desired pair of tools to a working position, a stripper and hold-down plate below the upper turret plate, a guide column supporting the stripper and hold-down plate, the guide column being axially slidable in the spindle, at least one guide pin coupling the upper turret plate and the stripper and hold-down plate for preventing relative rotation of the said plates, a plurality of stripping means on the stripper and hold-down plate corresponding to the said tools, drive means for lowering and raising a tool carried by the upper turret plate at the said working position, and means for concurrently lowering and raising the stripper and hold-down plate, the downward motion of the latter plate preceding that of the upper turret plate and the said latter plate remaining in contact with a workpiece disposed on the lower turret plate until the tool leaves the workpiece on its upward stroke.

3. Rotary punch press including a frame having upper and lower parts, a hollow spindle supported in the upper frame part, an upper revolving turret plate on the spin-

5 dle, a lower revolving turret plate coaxially journaled in the lower frame part, a plurality of aligned pairs of tools carried by the turret plates, the turret plates being rotatable together to bring a desired pair of tools to a working position, a stripper and hold-down plate below the upper turret plate, a guide column supporting the stripper and hold-down plate, the guide column being axially slidable in the spindle, at least one guide pin coupling the upper turret plate and the stripper and hold-down plate for preventing relative rotation of the said plates, a plurality of stripping means on the stripper and hold-down plate corresponding to the said tools, drive means for lowering and raising a tool carried by the upper turret plate at the said working position, and means for concurrently lowering and raising the stripper and hold-down plate, the downward motion of the latter plate preceding that of the upper turret plate and the said latter plate remaining in contact with a workpiece disposed on the lower turret plate until the tool leaves the workpiece on its upward stroke, the said means for raising and lowering the stripper and punch plate including a rotating shaft forming part of the said drive means, an eccentric on the shaft and acting on the said guide column to lower the stripper and hold-down plate concurrently with a tool at the said working position, and resilient means acting between the upper turret plate and the stripper and hold-down plate to bias the plates towards one another.

4. Rotary punch press as claimed in claim 3, the said guide column being open upwardly, and further including a plunger axially slidable in the guide column and bearing on the eccentric, and resilient energy accumulating means disposed between the plunger and the guide column to transmit axial forces therebetween.

5. Rotary punch press including a frame having upper and lower parts, a hollow spindle supported in the upper frame part, an upper revolving turret plate on the spindle, a lower revolving turret plate coaxially journaled in the lower frame part, a plurality of aligned pairs of tools carried by the turret plates, the turret plates being rotatable together to bring a desired pair of tools to a working position, a stripper and hold-down plate below the upper turret plate, a guide column supporting the stripper and hold-down plate, the guide column being axially slidable in the spindle, at least one guide pin coupling the upper turret plate and the stripper and hold-down plate for preventing relative rotation of the said plates, a plurality of stripping means on the stripper and hold-down plate corresponding to the said tools, drive means for lowering and raising a tool carried by the upper turret plate at the said working position, and means for concurrently lowering and raising the stripper and hold-down plate, the downward motion of the latter plate preceding that of the upper turret plate and the said latter plate remaining in contact with a workpiece disposed on the lower turret plate until the tool leaves the workpiece on its upward stroke, the said means for lowering and raising the stripper and hold-down plate including a rotating shaft forming part of the said drive means, a plunger axially slidably in the upper end of the guide column and projecting therefrom and bearing on the said eccentric, compression spring means disposed between the plunger and the guide column to transmit axial forces therebetween, whereby rotation of the said shaft causes the eccentric to act on the guide column via the plunger to lower the stripper and hold-down plate in advance of the downward movement of the tool resulting from said rotation.

6. Rotary punch press according to claim 5, including resilient means acting to bias the stripper and hold-down plate towards the upper turret plate.

7. Rotary punch press according to claim 6, in which the said resilient means consist of springs disposed on the said guide pins.

8. Rotary punch press including a frame having upper and lower parts, a hollow spindle supported in the upper frame part, an upper revolving turret plate on the spin-

spindle, a lower revolving turret plate coaxially journaled in the lower frame part, a plurality of tools carried by the turret plates and disposed in aligned pairs, means for rotating the turret plates together to bring any pair of tools to a working position, a rotatable stripper and hold-down plate disposed below and coaxially with the upper turret plate, a guide column supporting the stripper and hold-down plate and axially slidible in the said spindle, means for preventing rotation of the stripper and hold-down plate relative to the upper turret plate, a plurality of stripping means on the stripper and hold-down plate corresponding to the said tools, drive means for lowering and raising a tool carried by the upper turret plate at the said working position, a cam moving with the said drive means and co-operating with the said guide column to lower and raise the stripper and hold-down plate concurrently with the said tool, the downward movement of the stripper and hold-down plate preceding that of the tool and the said plate remaining in its lowered position until after disengagement of the tool from a workpiece disposed on the lower turret plate's corresponding tool.

9. Rotary punch press including a frame having upper and lower parts, a hollow spindle supported in the upper frame part, an upper revolving turret plate on the spindle, a lower revolving turret plate coaxially journaled in the lower frame part, a plurality of aligned pairs of tools carried by the turret plates, the turret plates being rotatable together to bring a desired pair of tools to a working position, a stripper and hold-down plate below the upper turret plate, a guide column supporting the stripper and hold-down plate, the guide column being axially slidible in the spindle, at least one guide pin coupling the upper turret plate and the stripper and hold-down plate for preventing relative rotation of the said plates, a plurality of stripping means on the stripper and hold-down plate corresponding to the said tools, drive means for lowering and raising a tool carried by the upper turret plate at the said working position, and means for concurrently lowering and raising the stripper and hold-down plate, the downward motion of the latter plate preceding that of the

upper turret plate and the said latter plate remaining in contact with a workpiece disposed on the lower turret plate until the tool leaves the workpiece on its upward stroke, the said means for lowering and raising the stripper and hold-down plate including a linearly moving rod forming part of the said drive means, an inclined plane on the said rod acting on the said guide column to lower and raise the stripper and hold-down plate concurrently with the tool motion resulting from movement of the rod.

10. Rotary punch press as claimed in claim 9, in which the said drive means is a toggle mechanism actuated by the said rod and the said inclined plane is provided on the upper side of the said rod, the guide column extending upwards to a level above the said plane, and further including a cam follower on the upper end of the guide column resting on the said inclined plane, and resilient means disposed between the upper turret plate and the stripper and hold-down plate for biasing the latter plate downwardly.
